EDWARD C. WHALEN, OF LAKWOOD, AND EARL W. McCLURE, OF WARRENSVILLE, OHIO.

COIN BANK.

Application filed June 4, 1923. Serial No. 643,337.

To all whom it may concern:

Be it known that we, EDWARD C. WHALEN and EARL W. McCLURE, both citizens of the United States, residing, respectively, at 5 Lakewood and at Warrensville, both in the county of Cuyahoga and State of Ohio, have invented a new and useful Improvement in Coin Banks, of which the following is a specification.

10 Our invention relates to banks or receptacles for coins.

The main object of our invention is a simple bank or receptacle for coins and provided with means to permit the insertion of coins 15 at one end but prevent removal of coins from this end, and further provided with means to permit the removal of coins only by the aid of an auxiliary instrument; in which bank the amount and the denomination of 20 money therein is always in sight from the outside of the bank; in which bank each individual row of coins is carried in a separate compartment; and which bank is easily carried in a pocket. Other objects will appear during the description of the bank 25 shown in the accompanying drawing.

As is well known, the saving of small coins leads to thrift. The bank of the present invention aims to aid in such thrift by providing a simple and convenient means to save 30 coins.

We attain our objects by certain bank structures adapted to accomplish our aims. One such structure is shown in the accompanying drawing in which Fig. 1 is a general perspective view of a bank embodying the features of our invention and showing the general appearance of this particular bank; Fig. 2 is a section, taken on a plane 35 (vertical) indicated by the line 2—2 in Fig. 1, showing the relations between the case and the cover, and the cap, and the partition, and the inlet protector, and the lock means for the cap; Fig. 3 is a section, taken on a horizontal plane indicated by the line 3—3 in Fig. 1, showing the partition and the auxiliary means for unlocking the cap; Fig. 4 is a fragmental sectional view, taken on a vertical plane indicated by the line 4 in Fig. 40 1, showing the locking mechanism for the cap; Fig. 5 is a perspective view of the partition employed in the bank shown; Fig. 6 is a perspective view of a modified partition; 45

Fig. 7 is a fragmental sectional view showing the inlet protector in relation to the partition. 55

Similar reference characters refer to similar parts throughout the views.

The bank shown in the drawing consists, principally, of the case A, the cover B, the 60 cap C, the partition D, and the inlet protector E.

The case A itself is open at each end and has the walls 10, 11, 12, and 13. The walls 12 and 13 are provided with the openings 14 65 and 15, respectively, for the purpose appearing presently. The walls 10 and 11 are duplicates, each being provided with the observation openings 16, 17, and 18, and with the corrugations 19, 20, and 21 to stiffen these 70 walls as well as the structure as a whole.

The cover B is provided with the inlet openings 22, 23, 24, 25, 26, and 27 in proper relation to each other and fits over and is permanently secured to one of the open ends 75 of the case A.

The cap C fits removably over the other of the open ends of the case A.

The partition D is formed of two duplicate parts, each part has the end flanges 28 80 and 29 and the intermediate flanges 30 and 31. Each of these parts is formed of one piece of material and the flanges 30 and 31 are formed by doubling up of the material. Both of these parts, when placed back to 85 back as shown, fit snugly into the inside of the case A; the flanges 28 and 29 bear against the inside of the walls 12 and 13 and the outer edges of the flanges 30 and 31 bear against the inside of the walls 10 and 11 90 as clearly seen in Fig. 3.

When these partitions are inserted in the case A, the channels 32, 33, 34, 35, 36, and 37 are formed in alignment with the inlet openings 22, 23, 24, 25, 26 and 27 respectively. 95

These channels and openings are here shown of one size to suit one particular species of coins, but it is obvious that they can be made of different size so that one bank can accommodate more than one species 100 of coins; in fact each of these openings and channels can be made of different size so that six different species of coin can be placed in one bank. When it is desired to accommodate more than six different species 105 of coin, or when more than six compart-

ments are desired in one bank, the number of channels and openings may be increased accordingly.

It is observed that all of the flanges of these partitions are of equal length and that the back walls of these partitions are cut away at the bottom between the flanges and that those portions of the flanges 30 and 31, which project below the walls of the partitions, are provided with the openings 38 and 39 respectively; the purpose whereof will appear presently.

The inlet protector E, made of spring steel or celluloid or other material having the qualities of a spring, is formed as an inverted V, has the teeth like prongs 40 to render the protector more resilient, and is disposed over the top of the two partitions with the ends of these prongs resting against the inside of the walls 10 and 11 of the case A as clearly seen in Fig. 2.

The spring latch F, made of spring steel, has the body 41 which is secured to the inside of the cap C by soldering, or spotwelding, or otherwise. The legs 42 and 43 project upwardly from the body 41 and the hooks 44 and 45 project outwardly from the legs 42 and 43 respectively and are disposed in the openings 38 and 39 respectively when the cap is locked to the case as seen in Fig. 4.

When it is desired to deposit a coin in the bank, such coin is inserted into one of the openings in the cover B until it abuts some of the prongs 40; the coin is then pushed in further by force whereby these prongs are forced inward sufficiently far to permit the coin to pass into this particular compartment. These prongs, due to their spring tendency, will again assume their original positions as soon as the coin has passed them. After a coin is so deposited, it can not be taken from the bank through the insert opening since the coin will, in such outward passage, engage the inner surfaces of the prongs and can not be moved further than this position since the prongs can not move out of the way and, therefore, prevent the coin from being removed from the bank through the inlet opening.

When it is desired to remove the coins from the bank, it is desirable that a special and auxiliary apparatus be employed for that purpose. Such an apparatus, and the application thereof, is shown in Figs. 3 and 4.

This apparatus has two jaws 46 and 47 adapted to guidedly slide on each other and each of these jaws has the bars 48 and 49, both rectangular in the present instance.

As shown in Figs. 3 and 4, this apparatus is now in position ready to open the lock formed by the hooks 44 and 45 engaging the openings 38 and 39. In order to bring this apparatus to the position as

shown, it is first extended sufficiently far (jaws sliding on each other) so that the inner ends of the bars 48 and 49 straddle the outside of the walls 12 and 13 of the case A. These jaws are then pushed toward each other, with the bars 48 and 49 registering with the openings 14 and 15 respectively, until these bars assume the position shown in Fig. 4 where the ends thereof abut the ends of the hooks 44 and 45 respectively. A further push on the jaws, toward each other, pushes the hooks 44 and 45 inward and out of the openings 14 and 15, thereby releasing the lock and permitting the cap to be removed from the case so that the contents of the bank can be removed through this now open end of the case. In order to insure alignment of the bars 48 and 49 with the openings in the case and with the hooks 44 and 45, it is preferred that this apparatus is formed with the abutments 50 bearing against the outside of the case.

When it is desired to again close the bank, it is only necessary to place the cap over the end of the case and press it thereon; the hooks will then automatically lodge in their respective openings.

Instead of forming the partitions of two pieces as described, it may be more economically formed in separate compartment units, each as a separate channel formation, as seen in Fig. 6; these separate units are assembled in the case to form the coin compartments required.

Modifications other than those pointed out may be made, therefore, without limiting ourselves to the precise construction and arrangement of elements shown and described.

We claim:

1. In coin banks, the combination of, a case, a plurality of partitions of channel section extending longitudinally within said case, said partitions placed side by side and back to back inside of said case, the backs of said partitions comprising a wall dividing the interior of said case into two main compartments, and the sides of said partitions dividing each of said main compartments into a plurality of coin compartments.

2. In a coin bank, the combination of, a case open at both ends, a cap permanently secured to one of said open ends and provided with coin inlet slots, a removable cap on the other of said open ends, a plurality of partitions of channel section extending longitudinally within said case, said partitions placed side by side and back to back inside of said case, the backs of said partitions comprising a wall dividing the interior of said case into two main compartments, and the sides of said partitions dividing each of said main compartments into a plurality of coin compartments one opposite each of said coin inlet slots.

3. In a coin bank, the combination of, a case provided with observation openings in the sides thereof, outwardly extending beads around said openings to strengthen the bank 5 structure, a plurality of partitions of channel section extending longitudinally within said case, said partitions placed side by side and back to back inside of said case, the backs of said partitions comprising a 10 wall dividing the interior of said case into two main compartments, and the sides of said partitions dividing each of said main compartments into a plurality of coin compartments.
- 15 4. In coin banks, the combination of, a case divided into a plurality of longitudinal coin compartments and provided with an opening in each edge wall near one end thereof, a removable cap on said one end of 20 the case below said openings in the edge walls, each of said compartments defined by a partition of channel section comprising a back and two sides, each of said sides at said one end extending below the bottom 25 of said back and provided with an opening, a lock secured to said cap and disposed within the innermost pair of said sides and provided with lock bolts engaging said openings in the sides when said cap is locked to said case, and an auxiliary means secured to the inside of said case and provided with openings to engage said lock bolts to lock said cap to said case, and an auxiliary means adapted to enter said case from each edge above said cap to disengage 30 both of said lock bolts from said openings to unlock said cap from said case and permit removal of said cap from said case 35 while said auxiliary means is in position thereon.
5. In coin banks, the combination of, a case divided into a plurality of longitudinal coin compartments and provided with an opening in each edge wall near one end
- thereof, a removable cap on said one end of the case below said openings in the edge walls, each of said compartments defined by a partition of channel section comprising a back and two sides, each of said sides at said one end extending below the bottom of said back and provided with an opening, a lock secured to said removable cap and disposed within the innermost pair of said sides and provided with lock bolts engaging said openings in the sides when said cap is locked to said case, and an auxiliary means for disengaging said lock bolts from said openings, comprising a body composed of two parts adapted to slide upon each other, and a bar on each of said body parts and each adapted to enter one of said openings in the edge walls to move said lock bolts out of said openings in the sides to permit the removal of said cap while said auxiliary means is in unlocking position on said case.
6. In a coin bank, the combination of, a case, a removable cap on said case, a lock mounted in said cap and provided with two lock bolts in alignment with each other, means secured to the inside of said case and provided with openings to engage said lock bolts to lock said cap to said case, and an auxiliary means adapted to enter said case from each edge above said cap to disengage both of said lock bolts from said openings to unlock said cap from said case and permit removal of said cap from said case while said auxiliary means is in position thereon.

EDWARD C. WHALEN.
EARL W. McCLURE.
